SUPPORT CHASSIS FOR AN ANALOG RECORDING INSTRUMENT

J. B. Shepard, 541 Kern, La Habra, Calif. 90631

Filed May 23, 1974, Ser. No. 472,842

Term of patent 14 years

Int. Cl. D10—04

U.S. Cl. D10—46

FIG. 1

FIG. 2

FIG. 3

FIG. 4

FIG. 5

FIG. 6

FIG. 1 is a front elevational view of a support chassis for an analog recording instrument showing my new design;

FIG. 2 is a rear elevational view thereof;

FIG. 3 is a left side elevational view thereof;

FIG. 4 is a right side elevational view thereof;

FIG. 5 is a top plan view of my new design; and

FIG. 6 is a bottom plan view thereof.

I claim:

The ornamental design for a support chassis for an analog recording instrument, as shown and described.
